WINDOW AND PROTECTIVE MATERIAL
THEREFORHarry G. Matthews, Great Neck, and Louis W.
Cole and Thomas M. Cole, New York, N. Y.

Application January 8, 1942, Serial No. 426,040

11 Claims. (Cl. 160—102)

This invention relates to windows and to protective material therefor.

One object of the invention is to provide protective material for glass windows whereby to eliminate or greatly diminish the danger to the occupants of a room or loft of a factory or other building from the destructive damage of air raids.

More specifically, it is an object of the present invention to provide glass windows with protective material which prevents or lessens to a considerable extent the danger of flying glass and other fragments which would otherwise occur and cause considerable damage and injury in the interior of the building and to persons inside the building in the event of an air raid.

A further object of the invention is to provide a protective material having the above described characteristics and also being highly useful for blackout purposes.

A further object of the invention is to provide glass windows with protective material secured thereto whereby to eliminate or decrease the likelihood of personal injury and property damage which might otherwise result from an air raid.

Another object of the invention is to attach the protective material to the window in such manner that the window may be opened when desired without detaching the protective material therefrom. This also provides means to allow the decrease in pressure which builds up inside a building due to the initial inrush of air when an explosion occurs.

A further object of the invention is the provision of means to prevent glass or panes from falling outwardly when the second reaction of the explosion takes place.

The above and other objects, features and advantages of the invention will be clearly understood from the following description, reference being had to the accompanying illustrative drawings of a preferred embodiment of the invention.

In the drawings:

Fig. 1 is a view of a piece of protective sheet material embodying the present invention;

Fig. 2 is a sectional view on the line 2—2 of Fig. 1;

Fig. 3 is an outer view, in elevation, of a factory window embodying the present invention, one of the panes of glass being broken away to show the protective material;

Fig. 4 is a fragmentary view of the inside of the window, parts of the protective material and elements of the latter being removed for the purpose of illustration;

Fig. 5 is a sectional view on the line 5—5 of Fig. 4;

Fig. 6 is an inner view in elevation of the swingable frame of the window illustrated in Fig. 3;

Fig. 7 is a fragmentary view of the inner surface of the protective material;

Fig. 8 is a fragmentary view of the inner surface of a sheet of glass provided with protective material and illustrates a modification;

Fig. 9 is a sectional view of the protective material shown in Fig. 8.

Referring now to the drawings more in detail, the invention is illustrated, as shown in Fig. 3, with reference to a factory window of a well known type which comprises a stationary main frame or sash 10 and a swingable frame 12 mounted therein so that a part of the window can be opened and closed as may be desired.

In this type of window the glass panels indicated at 14 are mounted in panel frames having metal frame members 16 which have substantially co-extensive parts 18 that project inwardly of the window beyond the planes of the glass panels or panes 14. The protective material 20 embodying the present invention is mounted on the inner surface of the window to completely cover all of the glass panes of the latter. It will be understood that while a window of one well known type is illustrated, the invention is applicable as well to other types of windows. Said protective material 20 and the manner in which the same is associated with the window will now be described in further detail.

As illustrated in Figs. 1 and 2, the protective material of the present invention comprises a layer of sheet material and more particularly a sheet of padding 22 consisting, as here shown, of layers 24 and 26 of felted fibrous material disposed at opposite sides of and in fixed relation to an intermediate sheet 28 of fabric of a relatively open weave whereby the adjacent fibres of layers 24 and 26 are inter-connected with each other through said fabric 28. Said fibrous material of layers 24 and 26 may consist of cow hair or of any other suitable fibres. While the thickness of padding 22 may vary it is preferably of the order of about one-half inch. Said padding material is preferably of the type which is placed under floor carpets for cushioning and other purposes, materials of this type being readily available on the market and sold under the trade name "Ozite" and other trade names.

A layer of wire mesh fabric 30 is secured to the inner surfaces of the sheet of padding 22

throughout the extent thereof. Said wire mesh fabric is secured to padding layer 22 preferably by stitches or wire staples 32 passing through padding 22 and folded over parts of the wire mesh at a multiplicity of points in the composite sheet. As illustrated in Fig. 7 the inner surface of the protective material is provided with grooves 34 pressed therein to receive the inwardly projecting parts of the panel frame members 16, thus to facilitate the application of the protective material to the window. It will be understood, however, that said grooves 34 may be omitted since the material is pliable and can be bent around said panel frame members.

The protective sheet material 20 of the present invention is secured to the window, preferably adhesively, and for this purpose a layer or coating 36 of any suitable adhesive substance such as, for example, a latex cement or glue, is interposed between the inner surfaces of the padding material 22 and the glass panes of the window and can be applied to either or both adjacent surfaces of the padding and of said glass panes, respectively, preferably throughout the areas thereof. Preferably, said protective material 20 is also secured to the inwardly projecting parts 18 of the panel frame members 16 by the securing devices 38 as illustrated in Figs. 4 and 5. For this purpose, advantage is taken of the fact that said panel frame parts 18, in a window of the type illustrated, have holes 40 passing transversely therethrough. Ordinarily, these holes are filled with putty applied in attaching the glass panels to the frame, and it will be understood, therefore, that preliminarily to attaching the protective material to windows of this type the putty is removed from these holes. A wire 42 is passed through these holes and through openings 44 in the padding, and the ends of the wire are twisted together over a metal washer 46 as indicated at 48 in Fig. 5. Thus, the protective sheet material is secured to the sash or frame at a multiplicity of points whereby to provide a secure attachment of the protective material to the window, this securingment being augmented by the adhesion of the padding material to the adjacent surface of the window glass.

As illustrated in Fig. 8, the protective material 20A comprises a sheet of padding which is preferably the same as material 20 described above except that the layer of wire mesh 30 is disposed between the inner and outer surfaces of the padding sheet, i. e., between fibrous layers 24 and 26. Said wire mesh preferably lies next to fabric sheet 28, the fibres of said layers 24 and 26 being felted together through the openings in sheet 28 and through the openings in said wire mesh. As described above in reference to Figs. 3 to 5, the protective material 20A is attached to glass 14 by a layer 26 of latex cement or glue which unites the adjacent glass and padding surfaces throughout said surfaces. If desired, wire staples or stitches (not shown) can be passed through the protective material in the same manner as illustrated at 32 in Figs. 1 and 2. In the case of protective material 20A, as well as protective material 20, the layer or sheet of wire mesh is substantially co-extensive with the area of the padding sheet and extends to the edge boundaries thereof.

In accordance with the present invention the protective material which is applied to the swingable frame 12 is separate from the protective material which is secured to the stationary part of the window. This is illustrated in Fig.

6 which shows an inner view of the swingable frame 12 detached from the main frame. Thus, the swingable frame 12 can be moved to a position for opening and closing the window as may be desired, and since the protective material is in fixed relation to the stationary and movable parts of the window, respectively, full protection is afforded while at the same time permitting the window to be opened when there is no danger of an air raid and to be immediately closed quickly and at a moment's notice when the danger of an air raid arises.

Since the protective material 20 or 20A is normally opaque it possesses a blackout characteristic as well as the protective characteristics with respect to preventing the flying of glass in case the window is shattered and preventing also the passage of explosive or other fragments which might otherwise pass through the window in the event of a nearby explosion of a bomb or a hit thereby near the building. It will be observed that the padding possesses a certain degree of resiliency and can stretch somewhat when struck, whereby to prevent the passage of flying material therethrough or to considerably reduce the destructive effect of such flying materials even if the latter completely penetrate said protective material. While as indicated, the material is opaque and therefore prevents the passage of light from the interior of the building through the window glass, it is preferred, for the purpose of adding safety, to coat the outer surface of the window glass with blackout paint or other substance which is preferably of the type which does not reflect light, so that in the event that flares are dropped on in the event of other illumination at the exterior of the building, the reflection of light by the window glass will be inhibited or reduced as much as possible. The inner surface of the protective material is preferably coated with white paint or is otherwise provided with a light reflecting surface.

While we have shown and described the preferred embodiment of our invention, it will be understood that the latter may be embodied otherwise than as herein specifically shown or described. It will be understood also that in the illustrated embodiment certain changes in the details of construction and in the arrangement of parts may be made. Therefore, we do not wish to be limited to the construction herein shown or described or to the specific protective material described except to the extent which may be required by the scope of the appended claims.

Having thus described our invention, what we claim and desire to secure by Letters Patent is:

1. A window comprising a sash in which the window glass is mounted, a layer of fibrous sheet material disposed over said window glass and having its inner surface closely adhered to said glass; and a layer of wire mesh positioned back of the inner surface of said sheet material in fixed relation to said material.

2. A window comprising a sash in which the window glass is mounted, a sheet of opaque padding material disposed over said window glass with one surface of said sheet positioned closely adjacent to the plane of said glass in fixed relation to said glass, and a layer of wire mesh positioned back of said surface of said sheet in fixed relation to said padding.

3. A window comprising a sash in which window glass is mounted, said window having an opening and said sash being movably supported

in said window for opening and closing said opening, and sheets of padding material disposed over said glass in said sash and adhered thereto, said padding material on the glass in said sash being movable with the latter.

4. A window comprising a sash in which the window glass is mounted, said window having an opening and said sash being in said window for opening and closing said opening, sheets of padding material disposed over said glass in said sash and adhered thereto, said padding material on the glass in said sash being movable with the latter, and layers of wire mesh fixed to said sheet of padding material, the wire mesh which is fixed to the padding material on said movable sash being movable therewith.

5. Protective material adapted to be associated with windows comprising a plurality of glass panels mounted in panel frames having members which project beyond the planes of said panels, said material comprising a sheet of padding and a layer of wire mesh in fixed relation thereto, said sheet material having preformed grooves therein to receive said projecting members whereby said sheet can be mounted in position over said frame members with one surface of said sheet abutting said glass panels.

6. Protective material adapted to be associated with windows comprising a plurality of glass panels mounted in panel frames having members which project beyond the planes of said panels, said material comprising a sheet of padding having preformed grooves therein to receive said projecting members whereby said sheet can be mounted in position over said frame members with one surface of said sheet abutting said glass panels.

7. Protective material adapted to be associated with windows comprising a plurality of glass panels mounted in panel frames having members which project beyond the planes of said panels, said material comprising a sheet of padding having a layer of fabric and a layer of felted fibrous material secured to said fabric layer, said sheet material having preformed grooves therein to receive said projecting members whereby said sheet can be mounted in position over said frame members with one surface of said sheet abutting said glass panels.

8. Protective material adapted to be associated

with windows comprising a plurality of glass panels mounted in panel frames having members which project beyond the planes of said panels, said material comprising a sheet of padding having a layer of fabric and a layer of felted fibrous material secured to said fabric layer, and a layer of wire mesh in fixed relation to said sheet of padding, said sheet material having preformed grooves therein to receive said projecting members whereby said sheet can be mounted in position over said frame members with one surface of said sheet abutting said glass panels.

9. A window comprising a plurality of glass panels mounted in panel frames having members which project beyond the planes of said panels, certain of said frame members having openings therethrough, padding sheet material disposed over said glass panels and over said frame members and having grooves therein to receive said panel members whereby said sheet can be mounted in position over said frame members with one surface of said sheet abutting said glass panels, and fastening members passing through said padding and through said openings in the frame members for securing said padding to the window.

10. A window comprising a plurality of glass panels mounted in panel frames having members which project beyond the planes of said panels, certain of said frame members having openings therethrough, padding sheet material disposed over said glass panels and over said frame members, and fastening members passing through said padding and through said openings in the frame members for securing said padding to the window.

11. A sheet of glass having protective material attached thereto in abutting surface relation, said protective material comprising a sheet of padding and a layer of wire mesh in fixed relation, said wire mesh being spaced from the adjacent surface of said sheet of glass and a layer of adhesive material interposed between the adjacent surfaces of said glass and padding and uniting said padding surface to said glass surface, the inner surface of said sheet of padding being non-metallic.
